W. H. BEMIS

OIL BURNING APPARATUS

Filed April 2, 1925

Inventor:
Walter H. Bemis
by Wright Brown Quincy May
Atlys.

UNITED STATES PATENT OFFICE.

WALTER H. BEMIS, OF MARLBORO, MASSACHUSETTS.

OIL-BURNING APPARATUS.

Application filed April 2, 1925. Serial No. 20,077.

To all whom it may concern:

Be it known that I, WALTER H. BEMIS, citizen of the United States, residing at Marlboro, in the county of Middlesex and 5 State of Massachusetts, have invented new and useful Improvements in Oil-Burning Apparatus, of which the following is a specification.

One object of this invention is to provide 10 an oil burner adapted to be conveniently installed in operative relation to an opening in a fire box and to project into the fire box, a jet composed of a mixture of air and atomized oil, the oil being raised from a body 15 maintained at a constant level and atomized when raised by a jet of compressed air.

Another object is to enable the force of 20 the jet and the relative quantities of air and oil comprising the same to be regulated by an operator at a location remote from the burner to increase or diminish the heat.

Another object is to provide improved 25 means whereby when the supply of gas to a pilot burner arranged to ignite the jet ceases, the operation of the burner is automatically discontinued.

I attain the above mentioned and other 30 related objects by the improvements herein-after described and claimed.

35 Of the accompanying drawings forming a part of this specification,—

Figure 1 shows in side elevation an oil 35 burning apparatus embodying the invention, a portion of the fire box with which the apparatus is associated, being shown in section.

Figure 2 is a longitudinal section showing 40 the structure which includes the air nozzle, the mixing nozzle and the regulating valve, and the leveling oil tank hereinafter described.

Figure 3 is an enlargement of a portion 45 of Figure 1, parts being shown in section.

The same reference characters indicate the 50 same parts in all of the figures.

In the drawings, 12 designates a mixing 55 nozzle for the emission of a jet of air and atomized oil. Said nozzle has at one end an oil-receiving chamber 13 communicating with the bore 14 of the nozzle. The chamber 13 surrounds an air nozzle or nipple 15, the bore of which is in alignment with the bore of the mixing nozzle, the discharge end of the air nozzle being spaced from the bore 14 by a narrow annular throat 16 through

which oil passes in a thin annular stream into the path of a jet of air from the air nozzle, so that the oil is atomized by and mixed with the air. An upright oil-conducting pipe 17 has a discharge end communicating with the chamber 13 at the upper portion of the latter as shown by Figure 2, the major portion of the oil pipe being below the discharge end. A body of oil is maintained at a constant level as hereinafter described, in the lower portion of the oil pipe 17, the normal level of the oil, indicated by the dotted line 18 (Figure 2), being below and in close proximity to the discharge end of the oil pipe or the point where the oil pipe enters the chamber 13, so that oil cannot flow by gravity into the chamber and is raised above the level 18 and caused to enter the chamber by a jet of compressed air emitted by the air nozzle 15. Owing to the close proximity of the oil level 18 to the discharge end of the oil pipe, oil is quickly drawn into the oil chamber 13 when air is emitted from the nozzle 15. The mixing nozzle is preferably screwed upon the base 70 of the air nozzle as shown by Figure 2.

The air nozzle is formed on or fixed to a block or body 19 containing an air chamber 20 communicating with the bore 21 of the air nozzle. The structure above described constitutes a burner which is supported in operative relation to the fire doorway or other opening in a heater having a fire box 23 as shown by Figure 1. Compressed air from the source of supply hereinafter described, enters the air chamber 20 through an air pipe 22, and passing through the air nozzle 15 induces a flow of oil into the oil chamber 13 through the upper portion of the oil pipe 17, the oil being atomized and 80 the mixture of oil and air projected from the mixing nozzle into the fire box 23. The mixing nozzle is preferably inclined as shown, so that the jet is directed inward and downward upon a bed 24 of any suitable material such as ashes or asbestos wool. If desired, however, the mixing nozzle may be otherwise arranged.

A pilot burner 25 is located in position to 85 ignite the mixture within the fire box and is supplied with gas as hereinafter described. To regulate the heat of the flame, I provide an air duct or by-pass 26 in the block 19 and mixing nozzle 12 below the bore 14, said duct having a tapered valve seat 27 com- 100

110.

municating with the air chamber 20. I also provide a needle valve 28, the stem 29 of which extends through guides 30 and 31 in the block 19 and is pressed by a spring 32 in the direction required to close the valve. The outer end of the stem is connected by a flexible cable or chain 33 guided by pulleys 34 with a manually movable regulating member or slide 35 located at a point remote from the burner, whereby the chain may be pulled in the direction required to open the valve 28, the spring 32 tending to close the valve when the member 35 is moved in the opposite direction. Any suitable means may be provided for maintaining the member 35 against the force of the spring in any position to which said member is movable by the operator. A graduated scale 36 may be provided to indicate different operative positions of the member 35.

When the needle valve 28 is closed, compressed air passes only through the air nozzle 15 and exerts a maximum oil lifting and atomizing force, so that a maximum degree of heat is developed. When the needle valve is opened, a part of the air escapes through the by-pass 26, so that the lifting and atomizing force of the air in the air nozzle is reduced and the heat is decreased to an extent determined by the opening of the valve. The location of the by-pass 26 below the bore of the mixing nozzle enables the air emitted from the by-pass to break up or atomize drops of oil that might otherwise fall uselessly from the discharge end of the bore 14, when the force of the air passing therethrough is reduced as described, this oil being suitably subdivided for ignition and projected into the jet emitted by the bore 14. To maintain oil at the desired level in the oil pipe 17, I provide a leveling oil tank 38 supported by a standard 39 and communicating with the oil pipe 17 through an oil-conducting arm 40 projecting from the lower portion of the tank, although if desired, the pipe 17 may be connected directly with the tank. The arm 40 is preferred, because it is of larger diameter than the pipe 17 and has sufficient strength to adequately support the latter and the structure formed by the mixing nozzle and the block 19. A body of oil is maintained in the tank 38 at the same level as that in the pipe 17 by an oil pump 41 preferably of the well known centrifugal type connected by a pipe 42 with a storage tank 43. A flow pipe 44 connects the discharge of the pump with the lower portion of the tank 38. A return pipe 45 connects the upper portion of the tank 38 with the storage tank.

The air pipe 22 is connected with the discharge of an air pump or blower 46 adapted to force air at an oil-atomizing and projecting pressure to the air chamber 20. The oil and air pumps are preferably operated in

unison by an electric motor 47, the shaft 48 of which is connected with rotors constituting elements of said pumps.

The pilot burner 25 is supplied with gas by a pipe 50 which communicates with a variable gas chamber formed in part by a rigid portion 51 and in part by a flexible diaphragm 52. Gas is supplied to the chamber by a pipe 53 communicating with a source of supply. When the gas is at normal pressure, the diaphragm 52 is bulged upward as shown by full lines in Figure 3. In case the gas supply fails, the diaphragm falls as shown by dotted lines.

Fulcrumed at 54 on a fixed support 55 is a detent lever composed of a relatively long arm 56 bearing on the diaphragm and provided with a weight 57, and a shorter arm or detent 58. The support 55 is preferably a part of a fixed bracket 59. Said bracket is provided with guides 60 in which a switch-operating rod 61 is vertically movable. Downward pressure is exerted on this rod by a spring 62. When the diaphragm is raised, the detent arm 58 is held thereby in position to engage a trip arm 63 pivoted at 64 to the bracket and provided with a slot 65 receiving a stud 66 on the rod 61. The trip arm is therefore releasably supported by the detent arm 58 in position to confine the rod 61 in a raised position against the pressure of the spring 62.

The electric circuit in which the motor 47 is included comprises conducting wires 163, 164, 165 and 166, as shown diagrammatically by Figure 1. A manually operable switch 67 located at any suitable point remote from the burner and preferably near the needle valve opening member 35, is adapted to close and break the circuit, and thus start or stop the operation of the burner. Between the circuit wires 165 and 166, is an automatic switch which in this instance includes a swinging arm 68 pivoted at 69, and spring contacts 70. When the trip arm 63 is engaged with the detent arm 58, the switch arm 68 bears on the contacts 70, and thus closes the circuit at this point. When the detent arm 58 is displaced as a result of the falling of the diaphragm, the spring 62 depresses the rod 61 and the switch arm 68 as shown by dotted lines, thus breaking the circuit (the same having been previously closed by the switch 67) and stopping the motor.

Operation.—The diaphragm being supported by normal gas pressure and the circuit being closed at the knife switch, the stop cock 25^a near the pilot burner 25 is opened and the gas is ignited. The circuit then is closed by the manually operated switch 67, the motor being thus started. The resulting operation of the blower and the oil pump causes the emission of a jet composed of a mixture of air and oil from

- the mixing nozzle, the jet being ignited by the pilot burner and projected into the fire box. When the needle valve 28 is in its normal closed position, the air from the air nozzle 15 has a maximum pressure or force and raises and atomizes a maximum quantity of oil. When the heat is to be reduced, the regulating member 35 is moved to open the needle valve, thus reducing the force of air from the air nozzle and the quantity of oil raised and atomized thereby, the air flowing through the by-pass 26 atomizing any oil that may drop from the discharge end of the bore of the mixing nozzle.
- 15 If the gas supply fails and the pilot light is extinguished, the diaphragm falls and the motor circuit is broken by the automatic switch, so that the motor stops and cannot be started by a manipulation of the starting switch until the gas supply is renewed.
- 20 I claim:

1. Oil-burning apparatus comprising a burner adapted to be supported in operative relation to an opening in a fire box, said burner including an air nozzle, an oil chamber surrounding the air nozzle, and a mixing nozzle having a bore of smaller diameter than the oil chamber, aligned with the air nozzle and communicating with the oil chamber, the discharge end of the air nozzle projecting into the bore of the mixing nozzle and being separated from said bore by a narrow annular throat, through which oil passes into the path of a jet from the air nozzle in a thin annular stream surrounding said jet, the burner being inclined to cause oil entering the oil chamber to gravitate to and fill said throat, so that a jet of air from the nozzle is entirely surrounded by oil from the throat, an oil pipe having a discharge end communicating with the oil chamber, means for maintaining a body of oil in the oil pipe below the discharge end thereof, and means for supplying air under pressure to the air nozzle to raise oil to the oil chamber and atomize the oil and form therewith a mixture which is projected into the fire box.
2. Oil-burning apparatus comprising a burner adapted to be supported in operative relation to an opening in a fire box, said burner including an air chamber, an air nozzle communicating with the air chamber, an oil chamber surrounding the air nozzle, a mixing nozzle having a bore aligned with the air nozzle and communi-
- cating with the oil chamber, a by-pass extending from the air chamber through the mixing nozzle and provided with a valve 60 seat, a needle valve movable in guides in the burner and adapted to close and variably open said seat, an oil pipe having a discharge end communicating with the oil chamber, means for maintaining a body of oil in the oil pipe below the discharge end thereof, means for supplying air under pressure to the air chamber to raise oil to the oil chamber and atomize the oil, and form therewith a mixture which is projected into the fire box, and needle-valve-adjusting means permitting the closing and a variable opening of the valve, the opening of the needle valve reducing air pressure in the air nozzle and the quantity of oil raised 75 and atomized thereby.
3. Oil-burning apparatus as specified by claim 2, the by-pass being located below the bore of the mixing nozzle, so that air emitted by the by-pass atomizes oil dropping 80 from the bore of said nozzle.
4. Oil-burning apparatus comprising a burner adapted to be supported in operative relation to an opening in a fire box, said burner including an air chamber, an air nozzle communicating with the air chamber, an oil chamber surrounding the air nozzle, a mixing nozzle having a bore aligned with the air nozzle and communicating with the oil chamber, a by-pass extending from the 85 air chamber through the mixing nozzle and provided with a valve seat, a needle valve movable in guides in the structure and normally closed on said seat; an oil pipe having a discharge end communicating with the oil chamber; means for maintaining a body of oil in the oil pipe below the discharge end thereof; means for supplying air under pressure to the air chamber to raise oil to the oil chamber and atomize the oil, and form therewith a mixture which is projected into the fire box; and needle valve-opening means including a manually movable member located at a distant point, and flexible connections between said member and the needle valve, the arrangement being such that when the needle valve is opened, air pressure in the air nozzle and the quantity of oil raised and atomized thereby are reduced.
- 100 5. In testimony whereof I have affixed my signature.

WALTER H. BEMIS.
